CLAIM

The ornamental design for a battery storage panel, as shown and described.

DESCRIPTION

FIG. 1 is a top plan view of a battery storage panel showing my new design;

FIG. 2 is a bottom plan view thereof;

FIG. 3 is a front elevational view, the rear being a mirror image thereof;

FIG. 4 is a right side elevational view, the left side being a mirror image thereof; and,

FIG. 5 is a perspective view thereof.

*Fig. 1**Fig. 2**Fig. 3*
